UNITED STATES PATENT OFFICE

131,623

DESIGN FOR A CRUTCH STAND

John A. Tackaberry, East Port Chester, Conn.

Application October 8, 1941, Serial No. 103,685

Term of patent 14 years

To all whom it may concern:

Be it known that I, John A. Tackaberry, a citizen of the United States, residing at East Port Chester, Fairfield County, State of Connecticut, have invented a new, original, and ornamental Design for a Crutch Stand, of which the following is a specification, reference being had to the accompanying drawing, forming part thereof.

Fig. 1 is a front elevational view of a crutch stand, showing my new design.

Fig. 2 is a side elevational view of the same.

The characterizing features of the design reside in the crutch stand disclosed comprising a cane-like column supported from a circular base and having a pair of curved cross tree elements near the top thereof, all as shown.

I claim:

The ornamental design for a crutch stand, substantially as shown and described.

JOHN A. TACKABERRY.
